US00D513978S

(12) United States Design Patent (10) Patent No.: US D513,978 S
Isono et al. (45) Date of Patent: * Jan. 31, 2006

(54) PACKAGE

(75) Inventors: Makoto Isono, Ashiya (JP); Nobuyuki Kitamura, Yawata (JP); Motoki Tamura, Takatsuki (JP)

(73) Assignee: The Procter & Gamble Company, Cincinnati, OH (US)

() Term: 14 Years

(21) Appl. No.: 29/207,350

(22) Filed: Jun. 11, 2004

(30) Foreign Application Priority Data

Dec. 12, 2003 (GB) 3015557

(51) LOC (8) Cl. 09-07

(52) U.S. Cl. D9/424; D9/420

(58) Field of Classification Search D9/414, D9/420, 423, 424, 431, 428, 432; 206/216, 206/223, 77.1, 278, 292, 547, 525, 822; 220/376, 220/350, 601; 229/116.1, 201, 182.1, 406

See application file for complete search history.
